PIPE ANCHOR MEANS

Malcolm S. Johnson and Harold E. Ray, Chicago,
Ill., assignors to Central Railway Supply Company,
Chicago, Ill., a corporation of Illinois

Application December 20, 1948, Serial No. 66,244

1 Claim. (Cl. 248—56)

1

Our invention relates to means for supporting and suitably anchoring the air pipes of the air brake systems disposed longitudinally beneath railroad cars; the object of the invention being to provide means adapted to be secured to a railroad car underframe whereby the pipes will be firmly held against vibration and movement and thus avoid ruptures in the pipe connections which would cause air line leaks and interference with proper air brake operation.

The invention has for its object the provision of an anchor of a simple nature which may be easily applied and which possesses stability and efficient holding power; the anchor consisting of a single piece or unitary structure which obviates the necessity of assembly of parts during application and hence eliminates the possibility of loss of parts when dismantled during maintenance.

Our invention also contemplates an anchor construction which may be easily applied to previously installed air lines or pipes without necessitating uncoupling or dismantling the pipes, thereby greatly facilitating installation and replacement and hence materially reducing labor time and expense; the anchor permitting the air pipe or line to be readily renewed if occasion should require without the necessity of dismantling or removing the anchor.

The objects and advantages of our invention will all be readily comprehended from the detailed description of the accompanying drawings wherein:

Figure 1 shows our improved anchor means in front elevation, applied to a pipe, shown in section, and secured to the vertical face of a car underframe member of which only a portion is shown.

Figure 2 is a vertical sectional view showing the initial position of the anchor means before screwing up the fastening element or nut.

Figure 3 is a side elevation of the anchor means applied to a portion of a pipe and the anchor means firmly secured to the vertical face of a car underframe member or sill which latter is shown in section.

Figure 4 is a front elevation of a modified form applied to a pipe shown in section and shown secured to the horizontal surface of a car underframe or side sill.

Figure 5 is a side elevation of the form shown in Figure 4, disclosing in dotted lines its initial position and in full lines showing its anchoring and final holding position.

Figure 6 is a front elevation of a modification

2 of the type of anchor means illustrated in Figure 1, with a pipe in section.

Figure 7 is a side elevation with the vertical portion of the car underframe in section; the initial or applying position of the anchor being shown in dotted lines and its fully applied and anchoring position being shown in full lines.

Figure 8 is a top plan view of the structure as shown in Figure 6, with the car underframe or sill in section.

In the exemplification of our invention as disclosed in Figures 1, 2 and 3, this single piece anchor is especially intended for anchoring the air line or pipe, of which a section is shown at 15, to a vertically disposed wall or face of a railroad car underframe or cross sill of which a portion is shown at 16, and which has previously been provided with a hole, as at 17, for passage of the pipe therethrough; the air lines or pipe 20 extend longitudinally of the railroad car.

The anchor means 18 preferably consists of a single piece casting or forging of suitable metal formed with an upstanding portion or vertical wall 19, shown provided with a substantially 25 flat rear face adapted to extend flush with the vertical web of the cross sill 16 and provided at its upper end with a bolt receiving hole at 20 to receive the fastening bolt or stud 21 secured to the cross sill and provided with a nut 22.

The lower end of the vertical portion 19 merges into the forwardly presented legs or portions 23 and united at the forward outer ends by the arcuate connecting web or stirrup-like portion 24 which is adapted to extend about the 30 lower side of the air line or pipe 15. The legs 23 project forwardly from the opposite vertical edges of the upper portion 19 and have vertically 35 arcuate inner opposing faces as shown in Figure 1 which merge into the horizontally arcuate saddle-like portion 25; the arcuate saddle portion 25, inner curved walls of the forwardly projecting legs 23 and the arcuate forwardly presented stirrup portion 24, when viewed from the front, define a vertically elongated opening which receives the pipe 15 with the stirrup portion 24 disposed about the lower side of the pipe while the saddle portion 25 extends across and in contact with the upper side of the pipe. The side 40 marginal portions of the upstanding wall 19 preferably are enlarged or provided with rigidifying ribs as at 26 which merge into the forwardly presented legs, with the juncture between the upstanding wall 19 and the lower marginal portions of the legs 23, namely the point 45 indicated at 27, preferably in a horizontal plane

50

55

slightly beneath the horizontal plane of the pipe engaging arcuate surface of the saddle-like portion 25.

The pipe receiving opening through the anchor is such that in order to slip the anchor onto the pipe the anchor must be tilted forwardly as shown in Figure 2, with the saddle portion 25 resting on the pipe while the stirrup portion 24 engages the bottom of the pipe. The anchor in its tilted position is slid toward the cross-sill 16 causing the juncture point 27 to engage the cross-sill in advance of the upper portion of the wall 19 whose aperture 20, however, is positioned to receive the stud bolt or pin 21 secured to the cross-sill. Upon screwing the nut 22 up tightly, juncture point 27 becomes a fulcrum point while upstanding wall 19 moves up flush against the cross-sill and the stirrup connected outer ends of the forwardly presented legs 23 tend to move upwardly, effecting a firm upward pressure on the pipe while the saddle portion 25 effects a firm downward pressure and somewhat wedging action on the pipe.

In order to provide greater gripping relation with the pipe, the saddle-like portion 25 and the stirrup portion 24 are shown provided with transversely disposed serrations as at 28, which will effect biting contact with the upper and lower sides of the pipe and effectively hold the pipe against longitudinal shifting or creeping tendencies.

Should an occasion arise for removing or renewing the air line or pipe, this may easily be accomplished by simply releasing the nut 22 sufficiently to permit the anchor means to be tilted forwardly thereby moving the gripping surfaces of the saddle-like portion 25 and those of the stirrup-like portion 24 out of contact with the pipe and permit the pipe to be easily withdrawn out of the anchor.

It is apparent that by changing the size of the pipe receiving opening our anchor means is adapted to various pipe sizes.

In order to prevent the anchor means turning during application or thereafter, we show the rear face of the upright member 19, at opposite sides of the pipe receiving opening, with rearwardly disposed lugs 29 which are adapted to extend into the somewhat enlarged opening in the vertical web of the cross-sill 16.

In Figures 4 and 5 we disclose a modified form of our improved means whereby the air line or pipe 15 may be anchored to the horizontal surface or underside of a car side sill 30. The anchor involves the vertically disposed saddle forming body portion 31 adapted to extend across the top of the air line or pipe 15, with the forwardly and downwardly extending legs or sides 32 uniting in the stirrup-like pipe engaging portion 33.

Instead of providing the pipe engaging saddle portion and stirrup portion with serrations or teeth as in the form shown in Figure 3, the saddle portion 31 and the stirrup 33 are provided with rubber or resilient arcuate pads or inserts 34 which may be bonded in place and additionally held against shifting by providing the convexed sides of the pads with a stud or headed projection 35 which may be forced through a suitable hole made in the saddle portion and in the stirrup portion as plainly shown in Figure 4. These resilient or rubber pads will effect a gripping or non-slipping relation with the air line or pipe and will also cushion the latter against vibration and chatter.

The upper end of the vertically disposed body 75

portion 31 extends forwardly to constitute a substantially horizontal rectangular bracket portion 36 adapted to extend flush with the under side of the side sill 30 and is provided with a pair of longitudinally spaced holes to receive the bolts or studs 37, 38 which are secured to the side sill 30.

The vertical distance between the horizontal planes of the saddle-portion 31 and the stirrup portion 33, as in the structure shown in the previous figures, is such that the anchor must be tilted slightly forward as shown in dotted lines in Figure 5 to enable the anchor to be easily slid onto the pipe and the rear hole in the bracket portion 36 brought into register with the bolt or stud 37, at which time the forward hole in the bracket arm 36 will also register with the bolt or stud 38. The nut on bolt or stud 37 is then screwed up into place, forcing the point of juncture between the vertical body portion 31 and the forwardly presented bracket arm 36, indicated at 39, into contact with the underside of the sill 30, so that tightening of the nut on bolt or stud 38 will cause the anchor to tilt on or at the point 39 and thereby force the saddle and stirrup pads into firm relation with the air line or pipe with the bracket arm 36 in flush relation with the bottom of the side sill.

In order to release the pipe, the nut on stud 37 should be slightly backed off and the nut on stud 38 released or removed, permitting the anchor to be tilted forwardly into the dotted line position shown in Figure 5, thereby moving the saddle and stirrup portions and their pads out of pressing contact with the air line or pipe.

It will be understood that instead of the resilient pads 34, the saddle and stirrup portions may be provided with teeth or serrations similar to those shown in Figure 3; and likewise, the pads 34 of the structure shown in Figure 4 may be employed in the type of anchor shown in Figure 3.

Figures 6 to 8 illustrate a modified form which enables the anchor means to be applied to previously installed air lines or pipes and also enables anchor replacement without requiring dismantling of the air line 15. The type of anchor shown in these figures is substantially similar to the type shown in Figure 1 and consists of the upright body portion 40 provided with a flat rear face to fit up flush against the vertical web of a cross sill of the car and which has been provided with a hole through which the air line or pipe 15 extends horizontally and longitudinally of the car.

One side marginal portion of the upright body 40, at its base, continues into a forwardly and downwardly sloping side leg 41. The leg 41 extends into a horizontal plane beneath the plane of the base of the upright body 40 and terminates in a horizontally disposed and arcuate pipe pillowng or engaging stirrup 42 arranged in contact with the lower side of the air line or pipe 15.

The body portion 40 at its base, as in Figures 6, 7 and 8, is provided with a transversely arcuate pipe straddling or engaging saddle-like cavity at 43, preferably provided with serrations as more clearly shown in Figure 7; and the rear face of the body 40 preferably extends slightly beneath the plane of the saddle-like portion where its juncture with the lower edge of the leg 41 may constitute a fulcrum point during application of the anchor, as shown by the dotted lines at 44. The direct vertical distance between the horizontal planes of the saddle-like portion 43 and the stirrup portion 42 is slightly less than the diameter of the pipe 15, thus necessitating the

anchor to be tilted forwardly as shown in dotted lines in Figure 7 in order to place the anchor in position on the pipe. Consequently when the nut is screwed up on the bolt or threaded stud 21 (which is welded or secured to the sill 16), the anchor will tilt about point 44 until the rear face is flush with the sill. This causes the serrations of the saddle-like portion 43 to shift downwardly (as shown in full lines in Figure 7) into firm pressing relation with the pipe 15, while the serrations of the stirrup portion 42 will be forced upwardly into firm pressing relation with the pipe 15 and effectively wedge the pipe against any longitudinal or independent movement.

In order to adapt the anchor to previously installed air lines or pipes, the leg at one side, viz. the right hand side in Figure 6, of the anchor, is omitted so as to provide a gap or lateral opening between the base of the upright body 40 and the free perimeter of the stirrup 42 as indicated at 45 by the dotted line and arrows in Figure 7. The opening 45 is arranged as shown in Figure 7 to permit the free end of the saddle portion 43 to extend down below the top of the pipe 15 and the free end of the stirrup portion 42 to extend a considerable distance above the bottom of the pipe and thus prevent lateral dislocation through sidewise movement of the pipe or anchor.

To apply the anchor it must be tilted forward sufficiently to bring the saddle portion and the stirrup portion substantially into the same vertical plane, at which time the anchor means may readily be slid sidewise onto the pipe and then placed in upright or vertical position preparatory to fastening it in place.

It is apparent that the upper bolt receiving end of the upright body portion may be given any desired configuration or angularity adapting it to the car underframe to which it is to be secured; the upright body portion with its downwardly and forwardly presented stirrup portion being the same in all forms and principle of operation.

The exemplifications that have been herein described are believed to be the simplest embodiments of the invention, but certain modifications are possible and may be made without,

however, departing from the spirit of our invention as defined in the appended claim.

What we claim is:

A pipe anchor comprising a rigid single piece metallic member provided with a flat faced elongated body portion apertured to receive fastening means for attachment to a supporting element and having an angularly disposed pipe supporting leg extending at a predetermined angle relative to the plane of said body portion with the juncture between the leg and body portion constituting a fulcrum point against the supporting element for tilting the leg upward; the anchor adjacent the fulcrum point having a pipe receiving passage whose axis normally is disposed outwardly and downwardly at a predetermined angle to the longitudinal axis of the pipe with the upper part of said passage formed to provide a relatively wide downwardly facing concaved pipe straddling portion and the lower part of the passage formed to provide a wide upwardly facing concaved pipe supporting portion spaced lengthwise of the pipe from the downwardly facing portion, both portions having friction providing surfaces extending over a substantial distance lengthwise of the pipe, the vertical distance between the two mentioned portions approximating the diameter of the pipe when the body portion is secured in place, the axis of the pipe-receiving passage being moved toward parallel relation with the lengthwise axis of the pipe when the body is secured to the supporting element whereby frictional gripping engagement across the top and about the bottom of the pipe is provided.

MALCOLM S. JOHNSON.
